UNITED STATES PATENT OFFICE.

LILLIAN CHARTERIS, OF NEW YORK, N. Y.

DESIGN FOR AN ANIMAL FIGURE OR SIMILAR ARTICLE.

Application filed September 7, 1922. Serial No. 3,643. Term of patent 3½ years.

To all whom it may concern:

Be it known that I, LILLIAN CHARTERIS, a citizen of the United States, residing at New York, in the county of New York and State of New York, have invented a new, original, and ornamental Design for Animal Figure or Similar Article, of which the following is a specification, reference being had to the accompanying drawing, forming a part thereof.

The design is shown in the accompanying drawing, wherein Figure 1 is a front view, Fig. 2 a side elevation and Fig. 3 a plan view of the animal figure.

I claim:

The ornamental design for an animal figure or similar article, as shown.

LILLIAN CHARTERIS.
